Primary Examiner — Ricky Pham(74) *Attorney, Agent, or Firm* — Nancy J. Flint, Esq.; Nancy J. Flint, Attorney At Law, P.A.(57) **CLAIM**

The ornamental design for a kryomixer, as shown and described.

DESCRIPTION

FIG. 1 is a right side view of a kryomixer showing my new design;

FIG. 2 is a left side view of a kryomixer;

FIG. 3 is a front view of a kryomixer;

FIG. 4 is a back view of a kryomixer;

FIG. 5 is a top view of a kryomixer;

FIG. 6 is a bottom view of a kryomixer; and,

FIG. 7 is a right side view of a kryomixer attached to a cryogenic fluid source.

Right side views not shown are mirror images of left side views. Any broken lines illustrative of environmental structure in the drawings are not part of the design sought to be patented.
